CLAIM

The ornamental design for a misting fan as shown and described.

DESCRIPTION

FIG. 1 is a front elevational view of a misting fan showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, front and left side perspective view thereof;

FIG. 9 is a top, rear and left side perspective view thereof;

FIG. 10 is a top, front and right side perspective view showing the misting fan in a first state of use;

FIG. 11 is a top, front and right side perspective view showing the misting fan in a second state of use;

FIG. 12 is a top, front and right side perspective view showing the misting fan in a third state of use; and,

FIG. 13 is a bottom, front and right side perspective view of FIG. 12.
